(57) **CLAIM**

The ornamental design for a portable collapsible hook device extended from the metal magnetic frame, all integrated and constructed to form a single structure, as shown and described.

DESCRIPTION

FIG. 1 is a perspective view of a portable collapsible hook device in an open position, showing my new design.

FIG. 2 is a left plan view thereof;

FIG. 3 is a right plan view thereof;

FIG. 4 is a front elevation view thereof;

FIG. 5 is a back elevation view thereof;

FIG. 6 is a top elevation view thereof;

FIG. 7 is a bottom elevation view thereof;

FIG. 8 is an alternate perspective view, shown in a closed position thereof; and,

FIG. 9 is an alternate front elevation view, shown in a closed position thereof.
